UNITED STATES PATENT OFFICE.

WILLIAM ALLEN PENDRY, OF DETROIT, MICHIGAN.

BUTTON-MAKING MACHINE.

SPECIFICATION forming part of Letters Patent No. 693,565, dated February 18, 1902.

Application filed March 2, 1901. Serial No. 49,606. (No model.)

To all whom it may concern:

Be it known that I, WILLIAM ALLEN PENDRY, a citizen of the United States, residing at Detroit, county of Wayne, State of Michigan, have invented a certain new and useful Improvement in Button-Making Machines; and I declare the following to be a full, clear, and exact description of the invention, such as will enable others skilled in the art to which it appertains to make and use the same, reference being had to the accompanying drawings, which form a part of this specification.

My invention relates to an improved button-making machine, having for its object a machine for this purpose whereby the entire operation of making completed buttons from suitable blanks may be carried out by a single machine rapidly and economically, various operations necessary for the construction of the completed buttons being carried out by the machine in a succession of steps or stages from the feeding of the button-blanks thereto until the finished result is obtained.

My invention has more special reference to a machine for making pearl buttons; but I would have it understood that I do not confine its scope or application thereto alone, as it may be used for the construction of buttons from other materials.

My invention consists of the constructions, combinations, and arrangements of devices and appliances hereinafter specified and claimed, and illustrated in the accompanying drawings, in which—

Figure 1 is a plan view showing my invention with the cover removed. Fig. 2 is a vertical section on the line 2 2, Fig. 1, showing parts in elevation. Fig. 3 is a horizontal section on the line 3 3, Fig. 2. Fig. 4 is a plan view of the table *d* with the revolving turret removed. Fig. 5 is a view in section on the line 5 5, Fig. 4. Fig. 6 is a detail view of the cam 57. Fig. 7 is a detail view of the cam 319 for reversing the button-blank. Fig. 8 is a view of one of the chucks in horizontal section on the line 8 8, Fig. 2. Fig. 9 is a front view of one of the mandrels and chucks embodied in Fig. 8. Fig. 10 is a view of one of the set of drills in vertical section on the line 10 10, Fig. 1. Fig. 11 is a vertical section of the button-reversing mechanism on the line 11 11, Fig. 12, showing parts in ele-

vation. Fig. 12 is a view of the button-reversing mechanism in vertical section on the line 12 12, Figs. 13 and 14. Fig. 13 is a top plan view of the button-reversing mechanism. Fig. 14 is a top plan view of portions of the reversing mechanism with the upper portions shown in Fig. 13 removed. Fig. 15 is a vertical section on the line 15 15, Fig. 12. Fig. 16 is a side elevation of mechanism shown in Fig. 15. Fig. 17 is a partial detail view of the bell-crank, showing the pin for the connecting-rod. Fig. 18 is a plan view, in horizontal section, on the line 18 18, Fig. 2. Fig. 19 is a side elevation of portions of the drill-rod - feeding mechanism. Fig. 20 is a view in rear elevation of one of the drills. Fig. 21 is a horizontal section on the line 21 21, Fig. 2. Fig. 22 is a view in horizontal section on the line 22 22, Fig. 10. Fig. 23 is a view in vertical section on the line 23 23, Fig. 8. Fig. 24 is a longitudinal section on the line 24 24, Fig. 1. Fig. 25 is a vertical cross-section on the line 25 25, Fig. 24. Fig. 26 is a vertical section showing parts in elevation, the section taken through the clutch 58, the hollow trunnion 12, and adjacent parts. Fig. 27 is a longitudinal vertical section through the mandrel and bearings of one of the grinding devices on the line 27 27, Fig. 24. Fig. 28 is a detail view of the mandrel-dog and its attachment. Fig. 29 is a plan view of one of the drilling mechanisms. Fig. 30 is an inverted plan view showing parts in section on the line 30 30, Fig. 2, said figure, in other words, illustrating features of the invention located above the section-line 30 30. Fig. 31 is a detail view of the bearing-plate *n* in perspective. Fig. 32 is a detail view, in vertical section, showing one of the bearings in which the shaft carrying one of the grinding-wheels 128 is journaled. Fig. 33 is a detail view of the mechanism for locking the mandrels carrying the drill-rods. Fig. 34 is a detail view in section of one of the internal mandrels and related devices carrying one of the drill-rods. Fig. 35 is a detail view, in rear elevation, showing the cam-plate and its attachments governing the vertical movement of the grinding-wheel for sharpening the drills. Fig. 36 is a view in vertical section on the line 36 36, Fig. 10. Fig. 37 is a plan view of said cam-plate and its attach-

ment, showing parts in horizontal section. Fig. 38 is a view in vertical section on the line 38 38, Fig. 1. Fig. 39 is a detail view of the bell-crank actuated by the cam 57, 5 the view being in perspective. Fig. 40 is a view in elevation of the mechanism shown in Fig. 41 viewed from the opposite side. Fig. 41 is a detail view of the blank-feeding mechanism in side elevation with the table in section. Fig. 42 is a view in vertical section on the line 42 42, Fig. 41. Fig. 43 is a plan view of the steel facing-tool mechanism, showing parts in horizontal section. Fig. 44 is a view in side elevation of portions of said mechanism, showing parts in vertical section. Fig. 45 is a detail view in perspective of the stop for the cutting-tool. Fig. 46 is a side elevation showing certain features of the cutting mechanism. Fig. 47 is a view in section on 20 the line 47 47, Fig. 44. Fig. 48 is a plan view showing the worm 205 and connected mechanism. Fig. 49 is a detail view in elevation, showing the worm and connected mechanism. Fig. 50 is a detail view, in side elevation, showing portions of the drill-rod-feeding mechanism, the worm being in section and the star-gear shown in dotted position.

I carry out my invention as follows:

A supporting-frame may be employed of 30 any suitable construction. As shown in the drawings, it consists of a base *a*, a spider *b*, a support *c*, a stationary table *d*, and a stationary race or track *e*, having a connecting-spider *f*, provided with a hub 267. A suitable inclosing case is shown at *g*, and a top or covering at *h*. A main driving-shaft is indicated at *i*, provided with a driving-pulley *j*. A shaft *k* is provided with a bevel-gear *l*, meshing with a gear *m* upon the shaft *i*. 40 The shaft *k* is also provided with a non-rotatable bearing-plate *n*, in which the driving-shaft *i* is journaled at one end, as shown at *p*. The opposite end of the driving-shaft is journaled in its bearings within the case *g*, as shown. The shaft *k* is journaled at its lower end in the plate *n* and at its upper end in the spider *b* and is provided at its upper end above the spider with a gear *r*.

Upon the stationary table *d*, as shown in 50 the accompanying drawings, are supported a blank-feeding device *s*, a grinding or back-ing mechanism *t*, a blank-reversing device *u*, grinding or facing wheels *v v*, steel facing-tool mechanism *w*, a series of drilling devices 55 *x*, a buffer *y*, and, if desired, a counter *z*. I would have it understood that I do not, however, limit myself to any definite number of grinding or facing wheels or to any definite number of cutting and buffing devices or to 60 any specific number of drilling devices, as my invention contemplates any desired number as coming within its scope. The particular construction and operation of the feeding, reversing, facing, cutting, drilling, and buffing devices will be hereinafter described.

The numeral 2 denotes a rotatable turret or table carrying a series of mandrels 3. In Fig.

1 I have shown a series of twelve mandrels; but I would have it understood that I do not limit myself to any particular number thereof, as my invention contemplates the employment of any desired number of mandrels to be carried by the revolving turret or table. The construction and operation of the mandrels will be subsequently explained. The 75 turret is preferably constructed with an outer rim 55 and with an inner rim 5, the outer rim being preferably of cylindrical form and the inner rim of angular form, as shown. In these rims the mandrels are supported, the 80 rims being connected by a suitable number of arms 6. The rim 55 travels in its rotation upon the race or track *e*.

The numeral 7 denotes a rotatable sleeve or hollow axle provided with a toothed disk 85 8 at its lower end, the upper extremity of the sleeve being rigidly engaged with the turret in any suitable manner. In the drawings the sleeve 7 is shown constructed with a flange 9 at its upper end, which may be secured in 90 any suitable manner to a corresponding flange 10 upon the inner rim 5 of the turret. The sleeve or axle 7 is actuated by means of a rotatable disk 11 upon a hollow trunnion 12, driven from the shaft *k*, as hereinafter explained. The disk 8 is arranged to be rotated one step at each complete revolution of the disk 11 in any suitable manner. The disk 8 is arranged to be rotated one-twelfth of a complete revolution upon each complete revolution of the disk 11. If twelve mandrels are used, as shown in the drawings, the disk 8 is accordingly provided upon its periphery with twelve recesses or notches 13, as shown in Fig. 21, while a roller pin or tooth 14 upon the 105 disk 11 engages in one of said recesses or notches and carries the disk 8 forward one-twelfth of a complete revolution. A lever 15, operating a locking-bolt 16, (both shown in dotted lines in Fig. 2,) engageable with the 110 turret 2, serves to hold the disk 8 and turret from rotation during the intervals of the stop movement of said disk.

It will be understood that the mandrels 3 are spaced one from another upon the turret 115 a distance apart corresponding to the stop movement of the turret, the various feeding, grinding, reversing, buffing, and drilling devices located upon the stationary table *d* being spaced one from another in a similar manner, so that as the turret revolves the mandrels will be moved by successive steps from one to another of said devices upon said table to present the button-blanks carried by the mandrels to said devices in successive order 120 125 until the button is completed.

The shaft *i* is provided with a sprocket-gear 17 for driving the feeding mechanism. Meshing with the beveled gear *l* is a series of gears for driving the grinding, buffing, and drilling mechanisms. Thus to drive one of the grinding devices *t* I provide a gear 18 upon a shaft 19, meshing with the gear *l*. The shaft 19 drives a pair of beveled gears 20, driving a

shaft 21, provided with a pulley 22, belted with said grinder through an intermediate counter-shaft 23. The other grinding and buffing devices are each similarly driven by gears 24 upon corresponding shafts 25, driving bevel-gears 26, each driving a shaft 27, provided with a pulley 28, belted with the corresponding grinding device.

To drive the several drills, gears 39 40 41 are employed, located upon shafts 42 43 44, respectively, said shafts being provided with pulleys 45 46 47, belted with corresponding parts of the drilling mechanism. One of the drills is belted with the shaft *i* by a pulley 45 thereupon. The gear *l* is inverted and is in the nature of a "knock-out" or "slip" gear to prevent breaking the machine should anything catch. Below the slip-gear *l* upon the shaft *k* is located a plate 53, having a hub 52 securely fastened to the shaft *k*. On said plate, between it and the gear *l*, is a fiber washer 30. Above the gear *l* is another plate 49, between which and the gear *l* is another fiber washer 29. Above the plate 49 is a pressure-plate 50, engaging the hub 52. Springs 51 intervene between the pressure-plate 50 and the plate 49. Upon the hub 52 is engaged a nut 54, whereby a desired tension of the springs 51 may be provided to secure the desired pressure of the plates 49 and 53 upon the gear *l* to drive the shaft *k*.

Through the hollow trunnion 12, as shown in Fig. 26, extends a shaft 56, carrying a rotatable cam 57 for operating the drills, as hereinafter to be described. Upon the shaft 56 is located a clutch 58, operated by a hand-lever 59, the clutch 58 being engageable with the trunnion 12. Said trunnion is provided with corresponding detents 60, with which the clutch 58 engages. The shaft 56 is provided with the gear 61, meshing with compounded gears 62 and 63, driven by a gear *r* upon the shaft *k*. In order to change the speed of the shaft 56 and mechanism driven thereby, the compounded gears 62 and 63 are made interchangeable, and the pin 64, upon which said gears are rotated, is secured in an elongated arc-shaped slot in the spider *b*. (Indicated in dotted lines at 65 in Fig. 18.) This permits the compounded gears to be brought into proper mesh with the gears *r* and 61, however the diameters of the gears 62 and 63 may vary. The trunnion 12 is provided with a gear 66 at its lower end, meshing with a gear 67, driving a gear 68 upon a vertical shaft 69, said latter shaft actuating the clutch mechanism in the mandrels 3.

I will next describe the construction of one of the mandrels 3.

As shown in Fig. 8, the mandrel is formed hollow, operating as a sleeve. The rims 55 and 5 are provided with bearings 70 and 71, in which the mandrel 3 rotates and reciprocates. The mandrel is provided with a friction-pulley 72, secured thereto, and whereby the mandrel is rotated when required. The pulley 72 is driven by a friction-pulley 73, the

shaft of which is carried in a yoke 74, having a movable engagement upon a bracket 75. This movement may be accomplished by a screw 76, by means of which the yoke may be raised if the friction-pulley should become worn, the yoke being held in given position on the bracket by means of a screw 77. Upon the shaft of the friction-pulley 73 is a pulley 78, driven by a belt 79, engaged upon a pulley 80 upon corresponding shafts 19 or 25, as the case may be, it being understood that each of the mandrels is provided with a friction-pulley 72, driven by a friction-pulley 73 in certain positions. By reference to Fig. 4 it will be seen that the pulleys 73 and 78 are secured upon the stationary table *d*, while the mandrels are carried by the rotatable turret. The mandrels are therefore only rotated when their corresponding friction-pulleys come into contact with the corresponding friction-pulleys secured to the table, the friction-pulleys 73, with their driving-pulleys 78, being located and arranged, as more particularly indicated in Fig. 4, at desired intervals for actuating the mandrel.

Within the mandrel 3 is a sleeve 81, threaded at one end, as indicated at 82, to receive a chuck or clamping device 83, which may be made tubular at its inner end. For convenience of manufacture the sleeve 81 may be threaded into a collar 84 at its forward end, the chuck or clamping device also being threaded into said collar, as shown. The outer extremity of the clamping device is divided into a series of clamping-jaws 85 of any desired number, four being shown in Fig. 9. Said jaws are preferably made flaring outwardly and constructed with inwardly-turned fingers 105 at their extremities to grasp the periphery of a button-blank, the outwardly-flaring portions of the chuck engaged against the inner adjacent surface of the mandrel 3, so that when the mandrel 3 is reciprocated the clamping-jaws will be opened and closed in a corresponding manner. The sleeve 81 is held from longitudinal movement in any suitable manner. For example, its inner end may be constructed with a flange 485, abutting against the adjacent end of the bearing 70, which will prevent the forward movement of said sleeve. A thrust-bearing 86 impinges against the outer face of said flange, preventing the opposite movement of said sleeve, said thrust-bearing held in place by a collar 87, having a threaded engagement therewith and upon the adjacent bearing 70. Within the sleeve 81 is a reciprocatory push-rod 88, provided at its forward end with a backing-piece 89, having an adjustable engagement with said rod, said piece, for example, having a threaded engagement with the rod, as indicated at 90, the backing-piece abutting against the button-blank, as shown in Fig. 8, preventing the button-blank from being forced inward while being operated upon. The rod 88 is pushed forward by a push-pin 91, operated by a cam 92 upon the shaft 69. The rod 88 is retracted by a spring

93. The push-pin is retracted by a spring 94. To cause the rod 88 to rotate with the sleeve 81, said rod is preferably squared toward its rear end, as shown. In Fig. 8 a washer 95 is provided with a square opening secured to the adjacent end of the sleeve 81. The sleeve 81 is made to rotate with the mandrel 3 in any suitable manner—as, for example, the inner end of said sleeve may be provided 10 with a key-pin 96, working in a corresponding slot 97 in the sleeve or mandrel 3. The mandrel or sleeve 3 is moved inwardly to release the jaws of the chuck on the work by means of a draw-plate (indicated at 98) provided 15 with bifurcated jaws 99, projecting downward and impinging against a numbering-plate 100, secured to the pulley 72. The draw-plate 98 is provided with a suitable stop, as indicated at 101, to limit its forward 20 movement. Said draw-plate is moved inward by means of draw-plates 102 on the shaft 69, actuated by a cam 103 upon said shaft, the draw-plates 102 being provided with a roll 104, contacting with the surface of 25 the cam 103. The draw-plates 102 are provided with a tapered roll 105, the draw-plate 98 being constructed with an undercut shoulder (indicated at 106) extending downward over the roll 105. The mandrels 3, together 30 with the draw-plates 98, with their draw-plates 102, are retracted by a spring within the mandrel, (indicated at 107, Fig. 8.) At the forward end of the mandrel 3 is a shroud 108 to keep the dust from the bearing 71. 35 The bearing 71 is locked in place by a nut 109. The bearing 70 is locked in place by the collar 87. A button-blank is indicated at 110. It will be obvious that the forward movement of the spindle 88 will force the button-blank 40 out of engagement with the jaws of the chuck.

It is obvious that when the button-blanks are being drilled the mandrels, with their chucks, must be stationary. This may be 45 accomplished in any suitable manner. As shown more particularly in Fig. 28, it is accomplished by means of a pawl 111, journaled to an arm 112, secured to the corresponding arm 6 of the turret by means of a bolt 113, 50 said pawl engaged with notches 114 in the periphery of the numbering-plate 100, secured to the corresponding pulley 72. The opposite end of the pawl extends down in the path of a trip 115 as the turret is rotated, the 55 trip serving to lift the pawl out of engagement with the corresponding pulley or numbering-plate, permitting its rotation to another notch. The trip 115 is formed upon the stationary race or track e. The dog is held in 60 engagement with the numbering-plate by means of a spring 415. To rotate the mandrel so as to bring the button-blank into proper position for the drill, the numbering-plate is provided with notches 114, and rotation is imparted to the pulley 72 by means of 65 a wiper 116, upon the upper edge of which the periphery of the pulley travels and by which

said pulley is rotated as the turret revolves step by step. The trip 115 and the wipers 116 are located upon the race e, upon which 70 the turret travels. Said wipers may be held in place in any suitable manner. In Fig. 23 a wiper 116 is shown supported upon springs 117, providing compensation for wear and keeping the wiper up, so as to properly contact with the pulley. The arms of the spider 75 fare preferably recessed to hold the wipers 116. The springs 117 are engaged upon bolts or rods 119, passing through a backing-piece 120, said rods provided with adjusting-nuts 80 121.

The draw-plates 98 reciprocate in ways (indicated at 122) secured to the arms 6 of the turret, as by bolts, (indicated at 113,) said ways being provided with depending arms 112, carrying the corresponding dogs 111. An elongated trip 115 is located opposite the several pulleys 73 and 78 to hold the pawl out of engagement with the numbering-plate of the various mandrels while said mandrels are rotated by being in contact with the corresponding friction-pulleys. Adjacent to the drilling devices the trips 115 are made short, so that the dogs 111 when tripped will again fall immediately on the periphery of the numbering-plates, so as to fall into the notches when 95 they come into position, and the mandrels will therefore be held rigidly in place while opposite the respective drills.

The grinding and buffing devices are similarly constructed, and I will next describe one of said devices, the same being shown in detail in Figs. 24, 25, 27, and 32, and the description of one of said devices will therefore answer as a description for all of them. Accordingly 123 denotes a shaft supported in bearings 124 and 125, said shaft being provided with a pulley 126, belted, as by a belt 127, with a corresponding pulley 22 upon the shaft 21, as already explained. Upon one 110 end of the shaft 123 is engaged a suitable grinding-wheel or buffing-wheel where necessary, (indicated at 128.) I prefer to engage the grinding-wheel or buffing-wheel with the shaft 123, as more particularly shown in 115 Fig. 27, in which the shaft 123 is shown constructed toward one end thereof with an elongated recess 129, in which is engaged a spindle 130, having a threaded engagement with said shaft toward the inner end of the spindle, as indicated at 131. The spindle toward the outer end of the shaft 123 is made cone-shaped, as indicated at 132, the adjacent end of the shaft being formed with a conical seat, (indicated at 133.) The spindle fits 120 loosely within the recess of the shaft 123, between the cone 132 and the threaded end thereof, permitting the cone 132 to be seated perfectly true upon the corresponding seat of the shaft. The spindle may be provided also with 125 a hexagonal or other suitably-formed head 134 for the engagement of a wrench therewith.

The grinding or buffing wheel 128 is pref-

erably mounted upon a rod 135, extended through the spindle 130, the inner end thereof formed with a head 136, seating in a correspondingly-shaped seat 137 on the inner 5 end of said spindle. Upon the rod 135 at each end of the grinding-wheel I preferably locate conical caps 138 and 139, the extremities of the grinding-wheel being correspondingly formed. Should the grinding-wheel 10 split, it will be held in place by said caps. Upon the outer end of the rod 135 is a nut 140. By this construction it will be seen that all the parts are held in true alinement, while should the grinding-wheel break and the rod 15 carrying the same become bent or injured said rod 135 may readily be removed from the spindle. The shaft 123 is provided with a thrust-bearing 141 to prevent end motion. The bearings 124 and 125 are each provided 20 with a metal bearing 142, said bearings provided with a screw 143 to tighten said bearings when worn upon the mandrel or shaft 123.

In order to move the grinding or buffing wheels inward against the button-blanks in 25 order that said wheel may operate upon the blanks, the bearings 124 and 125 are mounted upon a slide 144. The bearings 124 and 125 may be alined upon the slide 144 longitudinally of the shaft of the grinding or buffing 30 wheels in any suitable manner. Thus, for instance, said bearings may be constructed with elongated slots, as indicated, for example, in Fig. 1 at 145, through which bolts 146 engage said brackets upon said slide. In this manner the grinding and buffing wheels may be 35 alined to bring said wheels into exact position for their work.

The slide 144 is movable upon supporting-ways 147, secured to the table *d*. To impart 40 motion to said slide, it is provided with a downwardly-projecting bracket 148, with the lower end of which is engaged a bell-crank 149, fulcrumed to the table *d*. The lower arm of the bell-crank is provided with a cam- 45 roll 150, engaging with its corresponding cam 151, Fig. 4. As shown in said figure, to actuate the buffing-tool *y* connection is made with the corresponding bell-crank 149 through a connecting-rod 152, oscillatory arm 153, and 50 connecting-rod 154. To change the connection of the bell-crank 149 with regard to the slide 144 in order to advance the slide to or from the work, as may be desired, with the bracket 148 is engaged an adjusting-screw 55 155, preferably provided with a hand-wheel 156, said screw being threaded with said bracket and said bracket bolted to the slide 144 by a bolt 157, passed through an elongated orifice 158 in the slide, the bolt 157 being engaged 60 with the upper arm of the bell-crank 149, the table *d* being also provided with an elongated orifice, (indicated at 159.)

The series of drills *x* are all of similar construction, and I will now proceed to explain 65 the construction of one of them, as more particularly illustrated in Figs. 1, 10, 20, 29, 33, and 34.

Upon the table *d*, supported upon legs 160, is engaged an oscillatory bed 161, forming 70 also a guideway for the base of a cylinder 162, made reciprocatory upon said bed. Within the reciprocatory cylinder 162 is a rotatable cylinder 163, the latter cylinder being toothed on its periphery toward one end thereof, as indicated at 164. The toothed portion of said 75 cylinder meshes with a pinion 165, driven by a gear 166, the gear 166 being engaged in a bearing 167, bolted to the oscillatory bed 161 by a bolt 168 and by an additional bolt 169. The bolt 168 is a king-pin bolt and forms the 80 fulcrum on which the oscillatory bed 161 oscillates. The bearing 167 is provided with a tailpiece 170, through which the bolt 169 passes in its engagement with the bed 161, the bolt 169 being provided with a sleeve 171, engaged 85 in an arc-shaped slot 172 in the table *d*, so that the bolt 169 may oscillate with the tailpiece of the bearing as the bed 161 is oscillated about the pin 168, the bolt 169 keeping the bearing in proper alinement with the oscillatory bed. 90 The gear 166 is provided with an elongated trunnion engaged in the bearing 167, the trunnion being made hollow, so that the shaft 173 may pass very freely therethrough. Upon said shaft is engaged a clamping-dog 174, provided with a tailpiece 175, engaged with lugs 176 upon a collar 177, having a threaded engagement upon the adjacent end of the trunnion of the gear 166. This collar prevents the gear from endwise movement. One end 95 100 of the driving-shaft 173 is journaled in a bearing 178. One of the lugs 176 is provided with a set-screw 478, Fig. 20. The clamping-dog 175 is provided with a clamp-screw 179 to bind the clamp upon the shaft in any required position. The revolving cylinder 163 is formed 105 with front and rear heads united by an integral arm 180. In the heads of said revolving cylinder are journaled a couple of hollow drill-mandrels, (indicated at 181 and 182.) Within 110 said mandrels are drill-holders or internal mandrels, (indicated at 183 and at 184,) each of said internal mandrels carrying a drill-rod 185. Upon the outer mandrels 181 and 182 are engaged tight and loose pulleys, (indicated 115 at 186 and 187.) To cause the internal mandrels to revolve with the outer mandrels with which they are respectively engaged, one extremity of each of the outer mandrels may be slotted, as indicated at 188. The internal 120 mandrel is provided with a key (indicated at 189) to engage in the slot 188. It is found convenient in order to form the orifice for the drill-rods in the internal mandrels to groove the internal mandrels and to insert into the 125 inner ends of said grooves a filling-strip, (indicated at 190.) On the inner ends of the internal mandrels is engaged a split chuck, (indicated at 191.) The inner ends of the outer mandrels are formed with a nose 192, so formed 130 as to clamp the jaws of the split chuck tight upon the adjacent end of the drill-rod as the internal mandrels are forced forward. The internal mandrels are formed, as shown, with

a collar 193. Over said collar is engaged a nut 194, having a threaded engagement upon the corresponding outer mandrel, said nut abutting against the adjacent surface of the 5 corresponding collar. By this means the internal mandrel may be forced forward, causing the jaws of the split chuck to contact with the corresponding nosepiece to cause said jaws to bind suitably upon the corresponding drill-rod. The drill-rods are made to advance 10 through the corresponding mandrels as they are ground away in sharpening. To advance the drill-rods as required, I provide a yoke, (indicated at 195,) with which is engaged a 15 feed-screw 196, said feed-screw having a threaded engagement with the yoke, as indicated. The feed-screw is provided with a gear 197 to rotate said screw, said gear being keyed to the screw, as shown. The shaft of 20 the feed-screw passes entirely through the arm 180 and is provided with a nut 198 in a recess (indicated at 199) to take up the longitudinal movement of the feed-screw.

200 indicates a dust-cap.

25 Upon the end of the rotating cylinder is engaged a bridge-bearing 201, secured in place by a bolt 202 at one end thereof and by a bolt 203 at the other end thereof passed through an elongated arc-shaped slot (indicated at 204) in the end of said bearings. A worm-gear 205 is carried in said bearing, the same being provided with a star-wheel 206. Said worm meshes with a gear 207, having on its axis a pinion 208, meshing with an 30 intermediate gear 209, meshing in its turn with the gear 197. On the cylinder 162 is a post 210, (shown in end elevation in Fig. 20,) provided with a pin 211, which in normal position is in the path of the star 206, so that as 35 the rotating cylinder carries the star past the pin 211 the star will be rotated a quarter-turn, thereby revolving the feed-screw 196 to force forward the drill-rod. The yoke 195, with which the feed-screw has a threaded engagement, is engaged with a double-flange bushing (indicated at 212) sliding freely upon the internal mandrels carrying the drill-rods. The bushings 212 rotate within the corresponding extremities of the yoke and revolve 40 with said internal mandrels, said bushing being keyed to said internal mandrels by a sliding feather 213, which also acts as a pusher, the same being provided with a shoulder, as at 214, abutting against the adjacent 45 end of the drill-rod. Each of the bushings 212 is provided with a latch 414, fulcrumed toward one end, as indicated at 215, the opposite end of the latch engaging over a screw 216, the latch being so constructed as to lock 50 the feather 213, preventing end motion of the feather in the bushing. The lock is so constructed as to remain in locked position when the machine is running. The latch, to this 55 end, is formed with a heel at 217, projecting downward in such a position that when the mandrel 183 projects beyond the bushing the latch cannot be unlocked. The rotatable

cylinder 163 is constructed with an annular groove 218, and the cylinder 162 is provided with a pin 219, projecting into said groove 70 to prevent independent endwise movement of the rotatable cylinder. The bed 161 is oscillated on its fulcrum 168 by means of a tangent-screw 220, passed through a tailpiece of said bed, as shown, the ends of said screw 75 contacting with posts 221 and 222, so that when the said screw is rotated said bed will be correspondingly oscillated. Upon the mandrels 183 and 184 are located sliding collars 223 and 224, said collars provided with a 80 pin 225, projecting into the slot of the corresponding mandrel, said pin preventing the buckling of the drill-rod as it is being forced forward. When the corresponding bushing 212 strikes said collar, the collar will be 85 forced along therewith.

To lock the rotatable cylinder in position when one of the drills is in position to work, the said cylinder is constructed with tapered orifices. (Indicated in dotted lines in Fig. 29 90 at 226.) The outer cylinder is constructed with a sleeve 227, through which projects a bolt 228 to engage in the recess 226. 229 is a cam-plate fulcrumed upon a bracket or standard 230, as indicated at 231, said plate provided with a cam-groove 232. The bolt 228 is provided with a pin 233, provided with a cam-roll at its lower end engaged in the cam-groove 232. The cam-plate is provided with a depending post 234, through which passes 100 a screw 235, provided with a spring 236, and with a nut 237 to adjust the tension of the spring. When the inner cylinder is rotated to bring an orifice 226 adjacent to the end of the bolt 228, the forward motion of the cylinder and drills causes the roller or wiper of the bolt to traverse the cam-groove, giving a longitudinal motion to the bolt 228, which enters the corresponding orifice and holds the cylinder in engagement with said orifice during the operation of drilling a button-blank. 110 No greater force can be given to the bolt than that exerted by the spring 235 on the cam-plate, thus preventing breakage of the parts.

Upon each of the mandrels 181 and 182 is 115 located a number-plate 238, each provided with two notches (indicated at 239) diametrically opposite the one from the other. Fulcrumed to the outer head of the rotatable cylinder, as indicated at 240, are dogs 241 to engage in the corresponding recesses 239 when the corresponding number-plate is in proper position. The mandrels 181 and 182 are driven by a belt 242 when engaged with their respective pulleys 186 and 187. 120

125 I have already described the mechanism by which the interior cylinder 163 is rotated. The rotation of said cylinder is for the purpose of alternately bringing the respective drill-rods into position to be sharpened by a 130 suitable sharpening device, one of the drill-rods being in working position, while the other drill-rod is in position to be sharpened. The sharpening device, as shown, consists of an

emery-wheel 243, mounted upon a shaft 244, carried in a long cylindrical bearing 245 and driven by a pulley 246 upon said shaft. The bearing 245 has a sliding engagement in a hub 247 on an extended face of the cylinder 162. To control the vertical movement of said shaft, I provide a cam-plate 248, provided with a cam-groove 249, Figs. 35 and 37. The elongated bearing 245 is provided with an arm 250, carrying a cam-roll 251, engaged in the cam-groove 249 of said cam-plate. The cam-plate 248 is carried by the oscillatory bed 161, said bed to this end, as shown, being provided with depending studs 252 and 253, sleeved through a carrier-plate 254, upon which the cam-plate is secured. The oscillatory bed is also provided with a screw 255, provided with a recoil-spring 256, said screw having a threaded engagement with the carrier-plate 254. The screw 255 passes through the bed 161, and obviously when said screw is turned in proper direction the cam-plate will be adjusted vertically in a corresponding manner. The cam-plate will thus oscillate with the bed 161, and as the base of the outer cylinder 162 reciprocates to and from the work upon the oscillatory bed the pin 250 will ride back and forth in the slot 249, carrying the shaft of the emery-wheel upward and downward corresponding to the shape of the cam-slot 249, so that the emery-wheel may be dropped away from the edge of the drill until the drill is in grinding position.

To move the cylinders 162 toward and from the work, I provide the cam 57, already described. (Shown in detail in Fig. 6.) In said cam is engaged an arm 261 of a bell-crank lever 258, (indicated in detail in Fig. 39,) said arm provided with a cam-roll 259 in the groove 260 of said cam. The bell-crank lever is also provided with arms 262 and 263. With the arm 261 of the bell-crank 258 is connected a link 264, the opposite end of said link being connected to the base of the cylinder 162 through the medium of a pin 265, as indicated in Fig. 4. By means of said cam, the bell-crank 258, and the link 264, connected, as described, with the base of the cylinder 162, carrying the drills, said cylinder is moved to and from the work.

In order to move all the drill mechanisms forward and backward synchronously by the one cam 57, I provide additional bell-cranks 257, as shown in Fig. 4, constructed like the bell-crank 258, except that the arm 261 of the bell-crank 258 (shown in detail in Fig. 39) is omitted. The various bell-cranks 257 have their arms 263 connected the one with the other and with the arm 263 of the bell-crank 258. The arms 262 of the bell-crank 257 are connected the one with the other, preferably by intervening connecting-rods provided with a turnbuckle 266. It will be understood that the base of the cylinder 162 of each of the drill mechanisms is connected with the corresponding bell-crank 257 by means of a connecting-link 264, as already described. The

trunnion of the gear 166 is hollowed out, as shown in Fig. 10, to give ample room for the oscillation of the drilling mechanism without binding upon the shaft 173.

As shown in Fig. 2, the spider *f* is formed with a hub 267, within which is a bearing 268 and within which is the sleeve 7, already described, as shown in Fig. 2. The bearing 268 is arranged to be adjusted by means of a plate 269, connected with the hub 267 by bolts 270. The hub 31 of the toothed disk 8 is provided at its upper end with a gear 271, meshing with gears 272 upon the shafts 173, which rotate the cylinders carrying the drills.

273 denotes a stationary column passing through the sleeve 7 and in which is journaled the shaft 69. The upper end of said column is provided with an outwardly-projecting flange or collar 274 about the cam 92, against which impinge the push-rods 88. In this flange is also engaged the push-pin 91, hereinbefore described. Upon the upper end of the shaft 69 is a cam 275, provided with a spur 276 to contact with the push-pin 91. The shaft 69 is provided with a gear 277, meshing with pinions 278 and 279 upon corresponding shafts 280 281, (shown in Fig. 30,) carried in requisite bearings and provided, respectively, with bevel-gears 282 and 283, meshing with corresponding gears 284 and 285 upon corresponding shafts 286 and 287, said shafts carrying corresponding cams 151, already described. The shaft 280 is provided also with a gear 288, meshing with a gear 289 upon the shaft 290, driving a duplicate set of gears (indicated at 291) similar to the gears 282 and 284 and driving similar mechanism as that driven by the shafts 280 and 281. The gear 61 is provided with a cam 292, and the lever 15 is provided with a cam-roll 293 to engage said cam and whereby said lever is actuated, as hereinbefore described.

I will next describe the construction of the blank-reversing device *u*. (More particularly illustrated in Figs. 11, 12, 13, 14, 15, and 16.)

Upon the stationary table *d* is located a stationary way 294, upon which is engaged a reciprocating bed or housing 295, in which is mounted a horizontally-reciprocating spindle 296 and an upright rotatable spindle 297. The sliding bed or housing is engaged with the way 294 by means of a gib 298 and bolts 299. The spindle 297 carries at its upper end jaws 300 to receive the button-blank from the corresponding chuck or mandrel upon the turret. The said jaws are formed with an orifice therebetween (indicated at 301) in the line of reciprocation of the spindle 296. To carry the jaws upon the spindle 297, the bearing 302 of said spindle is elongated and provided with a thimble 303, united to said spindle by means of a plug 304, engaged upon said spindle and having a threaded engagement with said thimble. Spring-arms 305 engage said jaws upon said thimble. It will be seen that the thimble revolves with the spindle. The spindle 297 is provided with a

gear 306, as hereinafter explained. To raise and lower the spindle 297 to bring the jaws into alignment with the corresponding chuck, the bearing 302 is provided with a milled wheel 307, said bearing being threaded in the bed or housing 295. By this means the bearing may be raised or lowered as required, a set-screw 378 holding it in given position. To raise and lower the spindle 297 with the bearing, the spindle is provided with an annular groove 308, a screw 309 passing through the bearing into said groove. The thimble carrying the jaws 300 is preferably made detachable from the spindle 297 to permit the interchanging of said jaws for different sizes of button-blanks. To this end the plug 304 and the upper end of said spindle may have a tongue-and-groove connection, as shown at 310.

311 is a shaft carrying at its upper end a bifurcated crank-arm 312, engaging one end of the spindle 296 to reciprocate said spindle. The lower end of said shaft is also provided with a crank-arm 313, provided with a crank pin or roll 314, wiping on a cam 315, carried by a shaft 316.

Upon the spider *b* is journaled a gear 317, and upon a shaft 318 is a cam 319.

320 is a bell-crank oscillating upon a stationary stud 321. One arm of the bell-crank is provided with a roll 322, wiping in the cam 319. The other arm of the bell-crank is connected with the sliding bed 295 by means of an intermediate connecting-rod 323, attached to a stud 324, having a threaded engagement in the gib of said housing. By this means the housing is reciprocated. Upon the shaft 318 is also engaged a gear 325, meshing with a gear 326, and upon the shaft 316 is a gear 327, meshing with the gears 325 and 326.

328 is an oscillatory link engaged at one end upon the shaft 318, the opposite end carrying a stud 329, said stud connected with a link 330 upon the shaft 316. Upon the shaft 316 is a disk 331, provided with a crank-pin 332. Above the disk is a locking-plate 333.

334 is a star-wheel, which for convenience can be carried loosely upon the stud 324.

335 is a gear having a fixed engagement with the star-wheel 334 and meshing with the gear 306, heretofore described.

Upon the shaft 316 is the cam 315, against which the pin with which the crank 311 is provided engages.

55 The purpose of the reversing mechanism is to take a button-blank from an adjacent chuck, the blank being received by the jaws 300, the end of the spindle 296 being advanced partially into the orifice 301 between said jaws 60 sufficiently to form a backing for the blank as it is so received between said jaws, then to turn the jaws about one-half of a revolution, and then to force the blank back into the chuck by another advancement of the spindle 296, said spindle retracting after its first advancement partially into the orifice between the jaws in order to permit the turn-

ing of the jaws to present the opposite face of the blank to the chuck. The bed 295 is to be advanced to the chuck, said jaws advancing over the periphery of the blank as the jaws of the chuck are released therefrom. It will be understood that the button-blank projects over the jaws of the chuck sufficiently to permit the jaws 300 to advance partially over the periphery of the blank. The first advancement of the spindle 296 partially to the opening between the jaws is necessary to hold the blank in proper position. It will be seen that by the rotation of the shaft 318 the cam 80 319, operating the bell-crank 320, connected with the sliding bed or housing 295, said bed with the mechanism mounted thereon, is reciprocated. At the same time by means of the gears 325, 326, and 327 and the connecting-links 328 and 330 the shaft 316 is rotated, by which means the pin 332 is engaged with the star-wheel 334, whereby the gears 335 and 306 are actuated to give a half-revolution to the jaws 300. It will be understood that 90 when the jaws 300 advance to engage the button-blank the jaws of the chuck are disengaged from the blank and the push-rod 88 is advanced to force the button-blank into the jaws of the reversing mechanism and against 95 the face of the spindle 296, which has advanced into the orifice between the reversing-jaws, as already described. Before the reversing-jaws can be given a half-revolution the push-rod 88 is retracted and also the spindle 296. By the mechanism already described said jaws are given a half-revolution. The reciprocating bed or housing is then retracted from the chuck. Then the reversing-jaws are given a half-revolution. The bed 100 or housing is then again advanced toward the chuck until the jaws are in proximity to the chuck, when the spindle 296 advances and forces the blank into the jaws of the chuck. The bed or housing is then retracted from the 110 chuck to permit the revolution of the turret. To bring another chuck into position, the locking-plate 331 is recessed on one edge thereof, as indicated at 336, to allow the points of the star-wheel to turn when the pin 332 has 115 been engaged therewith. When said pin is out of engagement with the star-wheel, it will be seen that the wheel is in locking position.

It will be understood that the various cam-rolls may be held in engagement with the corresponding cams in any suitable manner, as by suitable spring tension.

The various grinding devices, buffing-tool, steel cutting-tool, and also the drills are kept 125 clear of dust by means of suitable exhaust apparatus, as an exhaust-chamber 337, with which exhaust-pipes 338 are connected, leading into proximity with said parts of the cutting-tool.

It will be understood that the spider *b* is provided with a series of counter-shafts 23, provision being shown therefor in Fig. 18, as upon connecting-arms 339, one of said coun-

ter-shafts being shown in Fig. 18 upon a connecting-arm 339, there being such a counter-shaft for each of the grinding and buffing devices.

5 The steel facing-tool mechanism *w* is constructed and operated as follows: Said tool, as shown more particularly in Figs. 38 and 43 to 47, is constructed with a rotatable cylinder 340, carrying rotatable shafts 341 and 342, upon which are mounted steel cutting-tools 343 and 344. The cylinder 340 is made rotatable, so as to carry the steel cutters alternately adjacent to a corresponding chuck and then to a grinding-wheel, (indicated at 383.) 15 Inclosing the periphery of the rotatable cylinder 340 is a non-rotatable cylinder 379, the latter cylinder effectually excluding the dust and dirt from the parts within the cylinder 340. The cutting-tool 343 is shown in the accompanying drawings in position for work when the cylinders are advanced to the work, while the tool 344 is shown out of working position and in position to be ground when the cylinders are retracted from the work and given a proper rotation. The shafts 341 and 342 are provided with worm-gears 381 382, operated by corresponding worms 384 385 upon a shaft 377, upon which is an additional worm 376, meshing with a worm 411 upon a shaft 25 412, provided with a worm-gear 413, meshing with a worm 414 upon a shaft 416. The rotatable cylinder 340 is preferably constructed with an intermediate cylinder-body 417, formed with a web or diaphragm 418, with 30 heads 419 and 420, and with a toothed portion 421, forming a gear by which the complete cylinder 340 is rotated. The various parts of the said cylinder, it will be understood, may be suitably bolted together. While I have shown 35 two turning-tools 343 and 344, I do not limit myself to any given number which may be employed. Upon the shaft 416 is a star-gear 422. Upon the outer cylinder 379 is a pin 423, projecting into the path of the star-gear, against 40 which the star-gear may strike when the inner cylinder is rotated, thereby causing the star-gear to rotate, the star-gear rotating in turn the worm-gears before described and causing a corresponding rotation of the turning-tools 342 and 344. The turning-tools may 45 have any desired conformation on the outer periphery thereof corresponding to the form desired to be produced upon the work thereby—as upon the surface of a button, for example. The turning-tools are constructed firmly of annular form and are then provided each with a gap or recess, as at 423, of any desired form to constitute a cutting edge. It 50 is evident that a turning-tool so constructed 55 may be readily ground or sharpened without disturbing the conformation of the cutting edge. My invention, as already observed, contemplates the mounting of such cutting-tools upon rotatable shafts within a rotatable 60 cylinder and by which the position of the tools may be made interchangeable, one turning-tool being in working position, while the

other turning-tool is in a position to be sharpened. My invention further contemplates means by which the turning-tools may be automatically sharpened when out of operation or working position. By making the shafts of the turning-tools revolvable the tools themselves may be given a proper rotation to compensate for the grinding away of the cutting-faces thereof. To rotate the cylinder 340, the same is geared with a train of gears (indicated at 345) driven from a gear 346 upon a shaft 347, the gear 346 meshing with a gear 348 upon a reciprocating and rotary sleeve or hub 366 upon a shaft 349, geared by a pinion 350 with the gear 271, said sleeve being mounted in a bearing 380. The grinding-wheel 383 is mounted upon a shaft 351, belted by a belt 352 with a pulley 353 upon a shaft 354, said shaft being belted with a shaft 355 by a belt 356, the shaft 355 being provided with a pinion 357, meshing with a gear 358 upon the shaft *i*, provided with the gear *m*, as already explained, meshing with the gear *l*. The shaft 351 of the grinding-wheel 383 is preferably mounted in a movable arm or bracket 424, said bracket having a jointed or hinged engagement upon a post 425, which may be provided with adjusting-collars 426 and 427, 90 by which said arm or bracket may be adjusted vertically, as may be required, as by an adjusting-screw 428, passed through one of said collars and impinging against the other of said collars, as shown. 100

429 is a spring exerting its tension against the arm 424 to restore said arm to normal position.

It is important that the chuck carrying the work, when it comes in front of the steel facing-tool, should have a higher speed than at other points of its rotation, and to effect its higher rotation the corresponding friction-wheel 73 is given a higher speed by means of a belt 359, belted upon a shaft 360, said shaft 105 being belted by a belt 361 with a shaft 362, (shown in Fig. 3,) the shaft 362 being shown broken away in Fig. 38. The shaft 362 is provided with a gear 363, meshing with the gear *l*. The diameters of the pulleys carrying the belts are such as to give a desired speed to the corresponding friction-pulley 73. The cylinder 340, carrying the cutters, is made reciprocating toward and away from the chucks, and to this end the cylinder 379 110 is mounted upon a slide 364, sliding upon a base 365, to which the bearing 380 is secured. The train of gears 345, together with the gears 346 and 348, with the shaft 347, are so carried as to reciprocate with the slide 364. 115 To this end the gear 348 is provided with the elongated sleeve or hub 366, having a sliding engagement with the shaft 349, which may be a squared shaft engaged therewith. To reciprocate the slide 364, I provide a bell-crank 367, actuated by a cam 368, said cam actuated by the shaft 318. (Shown in Figs. 4, 30, and 38.) The slide may be adjusted to its work 120 by an adjusting-screw 369, constructed and

actuated in a manner similar to the mechanism shown in Fig. 24. With the slide 364 is engaged a lever 430, said lever engaging the bracket 424 and obviously swinging said bracket on its fulcrum when the slide is sufficiently retracted, thereby throwing the grinding-wheel 383 away from the adjacent turning-tool. One arm of the lever 430, as the arm 431, impinges against the forward edge of the bracket 424, while the rear of the lever may be provided with a pin 432 to engage the bracket to the rear of the vertical center thereof. By extending the lever 430 to engage the bracket past its vertical center it is evident that the movement of the lever will first cause the arm 431 to move the bracket with the retraction of the slide to carry back the grinding-wheel, and the rear arm when in contact will cause the rapid movement of the grinding-wheel away from the turning-tool, permitting the position of the turning-tool to be shifted by the rotation of the cylinder 340. The table *d* may be constructed with a suitable opening 433, through which the shaft carrying the grinding-wheel may oscillate, together with a corresponding portion of the bracket 424.

On the table *d* is an adjustable stop 434 to engage the elongated hub on the shafts of the cutting-tools to prevent the cutters being advanced toward the work so far as to engage the jaws of the mandrels 3. The inner cylinder, with its cutters, may be held firmly in operative position while a given tool is making its cut in any suitable manner. The outer cylinder is preferably slotted and provided with ears 435, through which are passed bolts 436 for tightening the outer cylinder upon the inner cylinder. The cylinder 379 may be adjusted transversely to the reciprocation thereof to adjust the turning-tools to the work with greater accuracy in any suitable manner.

The operation of the steel facing-tool mechanism is as follows: The turning-tool in working position is non-rotatable while performing its work, the mandrel carrying the work being rotatable. The reciprocating slide advances the turning-tool toward the work by the mechanism already described. When the work is accomplished, the reciprocating slide is retracted, carrying the turning-tool away from the work, and at the same time the grinding-wheel is swung out of operative position, as above set forth. The inner cylinder is then permitted to rotate. A partial rotation is also given to both turning-tools to compensate for the wear in grinding.

The bell-crank 320, as shown in Figs. 11, 12, and 17, is constructed with an eccentric-pin 370, engaged with the connecting-rod 323.

In consequence of the wear of the chucks it is necessary to cause the slide carrying the reversing-jaws to have an adjustment so that said slide may be brought closer to the chuck, which may be accomplished by turning the pin 370, formed eccentrically on the crank 320.

The feeding device *s* for feeding the but-

ton-blanks to the chucks is constructed and operated as follows, the same being more particularly illustrated in Figs. 40, 41, and 42 of the drawings. The device, as shown, consists of a rotatable feed-wheel 371, constructed with a series of orifices 372 on its periphery, into which orifices the button-blanks are placed in any suitable manner, as by an attendant. This disk is rotated by a gear 373, meshing with a gear 374, supported upon a sliding bracket 375. Within the wheel 371 are located a series of spring-actuated spindles 386, corresponding to the number of orifices 372, the outer extremities of said spindles being adjacent to said orifices. Fulcrumed on the shaft 387 of the gear 374 is a vibratory lever 388, provided with a spring-actuated pawl 389 at one extremity thereof engaging the toothed periphery of the gear 374. With the opposite end of the lever 388 is connected a reciprocating rod 390, which upon being raised will obviously cause the pawl 389 to rotate the gear 374 one step, thereby actuating the gear 373 and the disk 371 in a corresponding manner one step, the distance traveled by successive steps of the disk 371 being sufficient to carry the orifices 372 one by one in succession around in front of the adjacent chuck and in position to deliver a button-blank to the jaws of the chuck.

As already described, the main driving-shaft *i* is provided with a sprocket-gear 17 for driving the feeding mechanism, a sprocket-belt 391 leading therefrom to a sprocket-wheel 392 upon a shaft 393, having its bearings in hangers 394. Upon the shaft 393 is engaged a double cam 395, having a cam-shaped periphery and also a cam-groove 396. A vibratory arm 397 is provided at its lower end with a pin or cam roll 398, engaged in the cam-groove 396, the rotation of the cam serving to vibrate said arm, said arm being fulcrumed intermediate its extremities, as shown at 399. The upper end of said arm is constructed with a finger or flange 400, projecting into the center of the wheel 371, between the inner ends of the spindles 386. A retracting-spring 401 connects one end of the arm 397 to a sliding carriage 402, said carriage carrying the feed-wheel 371 and the gears 373 and 374 and being arranged to slide in an opening 403 in a stationary bracket 404 on the table *d*. When the arm 397 is actuated, it will first pull on the spring 401, thereby advancing the carriage 402 and the feed-wheel to the chuck. When the feed-wheel meets the chuck, its further advancement is checked; but the further movement of the arm 397 carries the flange 400 to strike against the adjacent end of the spindle 386 in its path to force said spindle outward, and thereby push the button-blank in the corresponding orifice 372 into the jaws of the adjacent chuck. On the opposite movement of the arm 397 it strikes against a stud 405 to force backward the carriage 402. An upward movement is given to the rod 390 by bringing its lower extremity down to en-

gage a rocking step 406, fulcrumed, as at 407, upon a bracket 408 upon the periphery of the cam 396.

It will be apparent that since a step-by-step movement is given to the turret by its driving mechanism, as already described, a similar step-by-step movement will be given to the rotatable cylinders on the several drilling devices. Where, as in the accompanying drawings, the machine is provided with twelve chucks, the disk 8 will be constructed with twelve peripheral recesses, and the turret will be locked at each step by the bolt 16, the turret being constructed with twelve recesses 409, with which said bolt may engage. In a corresponding manner the gear 271 is constructed with twelve times the number of teeth on the gear 272, so that one-twelfth of the complete revolution of the gear 271 or one-step movement thereof will give to the gear 272 a complete revolution. The gear 166 should be constructed with one-half of the number of teeth that are upon the cylinder 163, thereby causing the cylinder to make one-half of a complete revolution at each step of the turret, thus exactly reversing the position of the two drills carried by said cylinder at each step movement of the turret to bring said drills alternately to the corresponding grinding-wheel.

To release the button from its chuck after it has been completed, the draw-plates 98 of the chuck when the chuck is in position to eject the button is drawn inward by means 35 of the draw-plate 102 through the action of the cam 103, as already described, whereby the jaws of the chuck are opened, the push-rod of the chuck then being actuated to eject the button, the jaws of the chuck remaining 40 open to receive the next button-blank.

I do not limit myself to the employment of the reversing mechanism alone, for should it not be desired to finish both faces of the button the reversing device might be omitted. Neither do I limit myself to the employment 45 of the feeding device, as the attendant might feed the blanks directly into the chucks, if preferred.

It will be understood in the operation of the 50 machine that as the turret revolves a given chuck carries its button-blank by the step-by-step movement of the turret to the successive operating device located upon the stationary table. At the point where the buttons are to 55 be ejected the machine may be provided with a discharge-chute 410, leading to any suitable receptacle. It will be evident that from the time a button-blank is fed to one of the chucks it is thereafter beyond the power 60 of the attendant to remove it. Any suitable counting device 2 may or may not be employed.

Fulcrumed to the cylinder 162 is a brake-lever 420. To this end the cylinder may be 65 provided with a fulcrum-block 421, to which one end of the lever is fulcrumed, as indicated at 422. A spring-actuated plunger 423 bears

against the brake-lever, said plunger being shown carried in a block 424, having a threaded engagement with the cylinder 162. On the 70 inner periphery of the cylinder 162 is a segmental groove 425, into which the brake-lever may be forced as the pulleys upon the drill-mandrels 181 and 182 are forced against said lever when the cylinder 163 is rotated. 75 The brake-lever will thus be caused to exert its tension upon the pulleys to stop the rotation of the corresponding mandrel. The extremities of the dogs 241 project into said segmental recesses 425 when in locked position, 80 said dogs being tripped out of locked position when the outer ends of the dogs strike the corresponding extremity of the segmental recess.

What is claimed as the invention is— 85

1. In a button-making machine, the combination of a rotatable turret having a step-by-step movement, hollow rotatable reciprocating mandrels, a sleeve within each of said mandrels provided with clamping-jaws to 90 hold the button-blanks, means to hold the sleeve in longitudinally-fixed position, a reciprocating push-rod within said sleeve to eject the blanks, means to release said jaws at desired intervals, a pulley upon said mandrel, a friction-pulley to drive the pulley upon the mandrel, and means to vertically adjust the position of the friction-pulley relative to the pulley upon the mandrel.

2. In a button-making machine, the combination of a rotatable turret having a step-by-step movement, hollow rotatable reciprocating mandrels, a sleeve within each of the mandrels provided with clamping-jaws to 100 hold the button-blanks, means to hold the sleeve in longitudinally-fixed position, a reciprocating push-rod within said sleeve to eject the blanks, means to release said jaws at desired intervals, a pulley upon said mandrel, a friction-pulley to drive the pulley upon 105 the mandrel, a vertically-adjustable yoke to carry the friction-pulley, means to hold the yoke in adjusted position, and means to drive the friction-pulley.

3. In a button-making machine, the combination of a rotatable turret having a step-by-step movement, a stationary table, hollow rotatable reciprocating mandrels carried by 110 said turret, a vertically-adjustable friction-pulley carried by said table to actuate the 115 mandrel, and means to drive said friction-pulley.

4. In a button-making machine, the combination of a rotatable turret, a stationary table, a mandrel provided with a reciprocating push-rod, a push-pin to actuate the push-rod, an upright rotatable shaft, a horizontally-rotatable cam upon the shaft to actuate the push-pin, a flange or collar about said cam against which the push-pin impinges, 120 and means to retract the push-pin and the push-rod.

5. In a button-making machine, the combination of a rotatable turret, a stationary

- table, a reciprocating mandrel, a horizontally-reciprocating draw-plate to actuate the mandrel, and a horizontally-rotatable cam to actuate the draw-plate.
5. 6. In a button-making machine, the combination with a rotatable turret, of a stationary table, a reciprocating mandrel provided with a number-plate, a horizontally-reciprocating draw-plate to engage the number-plate to actuate the mandrel, a rotatable shaft, and a horizontally-rotatable cam upon said shaft to actuate the draw-plate.
10. 7. In a button-making machine, the combination with a rotatable turret, of a stationary table, a rotatable shaft, a rotatable reciprocating mandrel provided with a number-plate, a horizontally-reciprocating draw-plate engaging said number-plate to actuate the mandrel, an additional draw-plate to actuate the first-named draw-plate, a horizontally-rotatable cam upon said shaft to actuate the additional draw-plate, and means to retract the mandrel and said draw-plates.
15. 8. In a button-making machine, the combination with a stationary table, of a grinding or buffing device constructed with a rotatable shaft provided with an internal elongated recess toward one end thereof, a spindle engaged with said shaft within said recess, an independent rod carried by said spindle, a buffing or grinding wheel mounted upon said rod, said spindle constructed cone-shaped at its outer end, and the adjacent end of the shaft constructed with a conical seat.
20. 9. In a button-making machine, the combination with a stationary table, of a grinding or buffing device constructed with a rotatable shaft provided with an internal elongated recess toward one end thereof, a spindle engaged with said shaft within said recess, an independent rod passing through said spindle, a buffing or grinding wheel mounted upon the outer end of said rod, said spindle constructed cone-shaped at its outer extremity, and the adjacent end of the shaft constructed with a conical seat, the inner end of said rod constructed with a conical head, and the inner end of the spindle constructed with a corresponding seat for said head.
25. 10. In a button-making machine, the combination with a stationary table, of a grinding and buffing device constructed with a rotatable shaft provided with an internal elongated recess toward one end thereof, a spindle adjustably engaged with said shaft within said recess, a rod engaged within said spindle to carry a grinding or buffing wheel, said spindle constructed cone-shaped at its outer end, the adjacent end of the shaft constructed with a conical seat, and means to adjust said spindle longitudinally of said shaft.
30. 11. In a button-making machine, the combination with a stationary table, a grinding or buffing device provided with a rotatable shaft having an internal elongated recess toward one end thereof, a spindle adjustably engaged with said shaft within said recess, a
- rod within said spindle, a buffing or grinding wheel upon said rod, conical caps upon said rod at each end of said wheel, the extremities of the wheel being correspondingly formed, and means to hold said caps.
35. 12. In a button-making machine, the combination with a stationary table, a grinding or buffing device provided with a rotatable shaft having an internal elongated recess toward one end thereof, a spindle adjustably engaged with said shaft within said recess, a rod within said spindle, a buffing or grinding wheel upon said rod, conical caps upon said rod at each end of said wheel, the extremities of the wheel being correspondingly formed, means to hold said caps, and means to align the wheel into position for work.
40. 13. In a button-making machine, the combination with a stationary table, of a reciprocating slide, a shaft having its bearings supported upon said slide, a buffing or grinding wheel carried by said shaft, and a thrust-bearing to prevent end motion of the shaft.
45. 14. In a button-making machine, the combination with a stationary table, of a reciprocating slide, a grinding or buffing device carried by said slide, a bell-crank to actuate said slide, and a cam to actuate said bell-crank, and means to adjust the connection of the bell-crank with the slide.
50. 15. A drilling device having in combination an oscillatory bed, a reciprocating cylinder carried upon said bed, a rotatable cylinder carried by the reciprocating cylinder, and means to prevent endwise movement of the rotatable cylinder in the reciprocating cylinder.
55. 16. A drilling device having in combination an oscillatory and reciprocating cylinder, and a rotatable cylinder carried by the first-named cylinder, said cylinders having a synchronous oscillatory movement.
60. 17. A drilling device having in combination a grinder, two drills interchangeable in position to bring the drills alternately to the grinder and to the work, and means to drop the grinder away from working position and restore the grinder into working position.
65. 18. A drilling device having in combination a stationary table, an oscillatory bed upon said table, a reciprocating cylinder upon said bed, and a rotatable cylinder carried by the reciprocating cylinder, said bed forming a guideway to the base of the reciprocating cylinder.
70. 19. A drilling device having in combination a stationary table, an oscillatory bed, a reciprocating cylinder carried by said bed, a rotatable cylinder within the reciprocating cylinder, and means to drive said rotatable cylinder, said means oscillatory with said bed.
75. 20. A drilling device having in combination a stationary table, an oscillatory bed, a reciprocating cylinder carried by said bed, a toothed rotatable cylinder within the reciprocating cylinder, a pinion to drive the rotatable cylinder, a gear to drive said pinion,

- and a bearing to carry said gear, said bearing oscillatory with said bed.
21. A drilling device having in combination a stationary table, an oscillatory bed, a reciprocating cylinder carried by said bed, a gear to drive said rotatable cylinder, a bearing to carry said gear, bolts uniting said bearing to the oscillatory bed, said bearing oscillatory with said bed, one of said bolts forming the fulcrum upon which said bed oscillates. 70
22. A drilling device having in combination a stationary table, an oscillatory bed, a reciprocating cylinder carried by said bed, a rotatable cylinder within the reciprocating cylinder, a pinion to drive the rotatable cylinder, a gear to drive said pinion, and means to prevent endwise movement of said gear, said gear oscillatory with said bed. 80
23. A drilling device having in combination a stationary table, an oscillatory bed, a reciprocating cylinder carried by said bed, a toothed rotatable cylinder within the reciprocating cylinder, a pinion to drive the rotatable cylinder, a gear to drive said pinion, a bearing to carry said gear, bolts uniting said bearing to the oscillatory bed, one of said bolts forming the fulcrum on which said bed oscillates, said table provided with an arc-shaped slot through which the other of said bolts travels to keep said bearing in alignment with the bed. 90
24. A drilling device having in combination a rotatable cylinder, a hollow mandrel carried by the cylinder, a drill-holder within the mandrel, and a drill-rod within the holder, said mandrel being slotted and said holder provided with a key to engage said slot, said holder provided with a chuck to engage the adjacent end of the drill-rod, and means to clamp the chuck upon the drill-rod. 95
25. A drilling device having in combination a rotatable cylinder, a hollow mandrel carried by the cylinder, a drill-holder within the mandrel, a drill-rod carried in said holder, said drill-holder provided at one end with a chuck and with a collar at the opposite end, a nut over said collar having a threaded engagement with said mandrel whereby the drill-holder will be advanced, and means to bind the chuck upon the drill-rod when the drill-holder is advanced. 100
26. A drilling device having in combination a rotatable cylinder, hollow mandrels carried by said cylinder each provided with a drill-holder, drill-rods engaged with said drill-holders, a feed-screw to advance the drill-rods, a worm-gear, a star-wheel carried by said worm, and mechanism driven by said worm to actuate the feed-screw. 110
27. A drilling device having in combination a reciprocating cylinder, a rotatable cylinder carried by said reciprocating cylinder, hollow mandrels carried by said cylinder, drill-holders carried by said mandrels, drill-rods carried by the drill-holders, a worm-gear, a star-wheel carried by said worm-gear, said reciprocating cylinder provided with a device projecting into the path of the star-wheel to rotate the star-wheel to revolve the feed-screw and advance the drill-rods. 120
28. A drilling device having in combination a reciprocating cylinder, a rotatable cylinder carried by the reciprocating cylinder, hollow rotatable mandrels carried by the cylinder, drill-holders within said mandrels and rotatable therewith, drill-rods carried by said drill-holders, a feed-screw, a yoke engaging said feed-screw constructed with bushings rotatable within the yoke and slideable upon the drill-holders, a key engaging the bushing with the drill-holder, and serving as a pusher to advance the corresponding push-rod. 125
29. A drilling device having in combination a reciprocating cylinder, a rotatable cylinder carried by the reciprocating cylinder, hollow rotatable mandrels carried by the cylinder, drill-holders within said mandrels and rotatable therewith, drill-rods carried by said drill-holders, a feed screw, a yoke engaging said feed-screw constructed with bushings rotatable within the yoke and sliding upon the drill-holders, a key engaging the bushing with the drill-holders serving as a pusher to advance the corresponding push-rod, and means to prevent end movement of the key in the bushing. 130
30. A drilling mechanism having in combination an oscillatory bed, a rotatable cylinder carried thereby, a reciprocating cylinder, drilling devices carried by the rotatable cylinders, and a screw to oscillate the oscillatory bed. 135
31. A drilling device having in combination a rotatable cylinder, hollow rotatable mandrels carried by said cylinder, slotted drill-holders carried by said mandrels and drill-rods carried by said holders, sliding collars upon said drill-holders constructed to prevent the buckling of the drill-rods, a yoke, a feed-screw engaged with the yoke to advance the drill-rods, bushings carried by said yoke, said bushings rotatable within the yoke and sliding upon the drill-holders and keyed thereto, said bushings when in contact with said collars, forcing said collars along with the movement of the bushings. 140
32. A drilling device having in combination a sharpening device, an oscillatory bed, a reciprocating cylinder upon said bed, a rotatable cylinder within the reciprocating cylinder, and drilling devices carried by the rotatable cylinder, said sharpening device carried by said oscillatory bed. 145
33. A drilling device having in combination a sharpening device, an oscillatory bed, a reciprocating cylinder upon said bed, a rotatable cylinder within the reciprocating cylinder, and drilling devices carried by the rotatable cylinder, said sharpening device carried by said oscillatory bed, a cam-plate carried by the oscillatory bed to cause a vertical movement of the sharpening device, and means to adjust the vertical movement of the sharpening device. 150

34. A drilling device having in combination an oscillatory bed, a reciprocatory cylinder thereupon, a rotatable cylinder within the reciprocatory cylinder constructed with orifices 5 on its periphery, a bolt carried by the reciprocatory cylinder to engage said orifices, and a cam to actuate said bolt, whereby the rotatable cylinder may be locked in position.
35. In a button-making machine, the combination of a stationary table, rotatable cylinders having a reciprocatory movement thereupon and provided with drilling mechanism, a cam, a bell-crank lever engaging the cam, and a link connecting the bell-crank lever with the rotatable cylinder to move said cylinder to and from the work.
36. In a button-making machine, the combination with oscillatory rotatable drilling mechanism, of a rigid driving-shaft to rotate said mechanism, said mechanism having an oscillatory movement without interfering with said driving-shaft.
37. In a button-making machine, the combination with oscillatory rotatable drilling mechanism, of a gear to rotate said mechanism provided with an elongated hollow trunnion, and a driving-shaft passing freely through said trunnion, whereby said trunnion may be oscillated without interfering 30 with said driving-shaft.
38. The reversing mechanism herein set forth having in combination a vertical rotatable spindle, an elongated bearing carrying said spindle, a thimble upon the upper end 35 of said bearing rotatable with said spindle, and a button-blank-holding device carried by said thimble.
39. The reversing mechanism herein set forth having in combination a vertical rotatable spindle, a plug detachably engaged upon the upper end of said spindle and rotatable therewith, an elongated bearing carrying said spindle, a thimble upon the upper end of said bearing engaged with said plug, and jaws 45 provided with spring-arms connected with said thimble.
40. In a button-making machine, the combination of a stationary table, a rotatable turret, means to give to the turret a step-by-step 40 movement, a series of hollow rotatable reciprocatory mandrels carried by said turret, a pulley upon the mandrel, a friction-pulley to drive the pulley upon the mandrel, a vertically-adjustable yoke to carry the friction-pulley, means to drive the friction-pulley, a sleeve within each of said mandrels provided with clamping-jaws to hold the button-blanks, means to hold the sleeve in longitudinally-fixed position, a reciprocatory push-rod 55 within said sleeve, means to release said jaws at desired intervals, a push-pin to actuate the push-rod, a rotatable shaft, a cam upon said shaft to actuate the push-pin, a collar about said cam against which the push-rod impinges, means to retract the push-pin 60 and the push-rod, a draw-plate to actuate the

mandrels, a cam upon said shaft to actuate the draw-plate, and means to hold the mandrels in stationary position at stated intervals.

41. In a button-making machine, the combination of a stationary table, a grinding and buffering device having a reciprocatory engagement upon said table, said device constructed with a rotatable shaft provided with an elongated recess toward one end thereof, a spindle adjustably engaged within said recess, a rod carried by said spindle, a buffering or grinding wheel carried by said rod, said shaft constructed with a seat at its outer end, and said spindle with a corresponding portion intermediate of its extremities to engage said seat, and means upon said rod at each end of the wheel to hold the wheel in position.

42. In a button-making machine, drilling mechanism embodying in combination a table, of an oscillatory bed upon said table, a reciprocatory cylinder upon said bed, a rotatable cylinder carried by the reciprocatory cylinder, a grinding device oscillatory with said bed, rotatable mandrels carried by the rotatable cylinder interchangeable in position to bring the drills alternately to the grinding device and to the work, means to move the grinding device toward and from the work, driving mechanism oscillatory with said bed to drive the rotatable cylinder, a rigid driving-shaft to drive said mechanism, said bed having an oscillatory movement without interfering with said driving-shaft.

43. In a button-making machine, the combination of an oscillatory bed, a support therefor, a reciprocatory cylinder upon said bed provided with a hub, a grinding device oscillatory with said bed, said grinding device embodying a shaft provided with a grinding-wheel, an elongated bearing for said shaft having a sliding engagement in said hub, means to rotate said shaft, a cam-plate carried by the oscillatory bed, an arm carried by said bearing engaged with the cam-plate to reciprocate said bearing, whereby the grinding-wheel will reciprocate with the reciprocation of the reciprocatory cylinder.

44. In a button-reversing mechanism, the combination of a reciprocatory support, a vertical rotatable spindle, an elongated bearing carried by said support and carrying said spindle, a thimble on the upper end of said bearing, a button-holding device carried by said thimble, a plug detachably engaging said thimble with the upper end of said spindle and rotatable with the spindle, and a reciprocatory spindle advanceable toward and from the button-holding device.

In testimony whereof I sign this specification in the presence of two witnesses.

WILLIAM ALLEN PENDRY.
